US00D999802S

(12) **United States Design Patent** (10) **Patent No.:** **US D999,802 S**
(45) **Date of Patent:** **** Sep. 26, 2023**

(54) **VIDEO CONFERENCE TERMINAL**

(71) Applicant: **Shenzhen Oceanwing Smart Innovations Technology Co., Ltd,**
Shenzhen (CN)

(72) Inventors: **Kebi Ding**, Shenzhen (CN); **Hyungwoo Yoon**, Shenzhen (CN)

(73) Assignee: **Shenzhen Oceanwing Smart Innovations Technology Co., Ltd,**
Shenzhen (CN)

(**) Term: **15 Years**

(21) Appl. No.: **29/813,791**

(22) Filed: **Nov. 1, 2021**

(51) LOC (14) Cl. **16-01**

(52) U.S. Cl.

USPC **D16/202**

(57) **CLAIM**

The ornamental design for a video conference terminal, as shown and described.

DESCRIPTION

FIG. 1 is a front top perspective view of a video conference terminal showing our new design in an open state; FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is front, top perspective view thereof shown in a closed state.

The broken lines in the drawings depict portions of the video conference terminal that form no part of the claimed design.

1 Claim, 9 Drawing Sheets
